UNITED STATES PATENT OFFICE

2,133,600

TERMINAL POST SUPPORT AND HEEL COVER

Norman D. Vea, Dover, Ohio, assignor to Knapp-Monarch Company, St. Louis, Mo., a corporation of Missouri

Application March 12, 1938, Serial No. 195,534

5 Claims. (CL. 219—25)

My invention relates to sadirons and particularly to electric irons wherein a detachable guard supplied with a plug is ordinarily used for attachment to terminal posts on the iron. Among 5 the objects of my invention is the provision of a new and improved sadiron structure comprising the formation and adaptation of a metallic member adapted to serve as a support for the terminal posts and simultaneously provide a cover or closure for a portion of the iron casing commonly known as the heel.

Another object is the provision in an electric sadiron structure of a mounting for the terminal posts supplied by a single separate metallic part 15 which is clamped in the iron between sole plate and casing and which acts also in the nature of a columnar reinforcement between the sole plate and the casing.

Still another object is the provision in an electric 20 sadiron of a combined support for the terminal posts and cover for the under side of the heel which is made from a single stamping provided with means for engaging portions of the casing and adapted to be clamped into position against 25 the sole plate of the iron by the casing wherein it is firmly supported by pressure and friction in such a manner as to provide a solid base for the terminal posts while at the same time acting as a reinforcement for the casing or shell adjacent the 30 point where the terminal posts are attached.

With these and other objects in view my invention consists in the construction, arrangement and combination of the various parts of my device whereby the objects contemplated are attained as hereinafter more fully set forth and 35 pointed out in my claims and illustrated in the accompanying drawing in which:

Fig. 1 is a small scale side elevation of an iron with the device installed therein.

40 Fig. 2 is a fragmentary longitudinal elevation partly in section showing the rear portion of an iron with the device installed.

Fig. 3 is a top view of the rear portion of the iron partially in section taken on the line 3—3 of 45 Fig. 2.

Fig. 4 is a top view of the stamping forming the combined terminal post support and heel cover, and

Fig. 5 is a cross sectional view taken on the line 50 5—5 of Fig. 2 looking in the direction of the arrows.

In the construction of electric sadirons many factors must be taken into consideration when it is desired to build a rugged structure which because of weight of the iron alone is subject to a great deal of strain and abuse. It is furthermore essential to reduce the manufacturing cost of devices of this sort to a figure as low as possible in order that the manufacturer may be able to meet 55 competition in this highly developed art. Not

only must material costs be reduced to a minimum but the number of operations necessary to assemble the parts must be made just as few as possible and this can be accomplished in many instances by reducing the number of separate individual connections which must be made in order to secure all of the parts together. Another factor which cannot be overlooked during this simplifying process is the inevitable requirement of safety which is especially necessary in electric 10 appliances of this sort designed for household use.

In the invention disclosed, meeting to a large extent the rigid requirements above recited, there has been provided a structural unit integral in 15 itself, serving a plurality of purposes and requiring a minimum of operations to install it in an appliance. In the embodiment shown the part in question is composed of a sheet metal stamping formed substantially in the shape of the letter Z as viewed in cross section providing a plate or support at the top leg to which terminal posts may be attached and extending rearward at the bottom leg to close a cavity formed at the rear of the iron by the application of a shell or casing 20 extending rearward to form what is known as a heel or heel rest.

As shown in the drawings an electric iron having a base A is provided with a handle B for manipulating it over an ironing board. A control D is provided for turning the iron on and off.

The base is composed of a sole plate 10 within which is embedded a heating element 12 and surmounting the sole plate is a weight member 14 attached thereto. Above the sole plate and weight is a shell or casing 16 which entirely covers the base portion of the iron and extends rearward at 18 in the form of a hollow heel or heel rest. The casing is secured to the sole plate structure by means of screws 20 threadably engaged in the weight 14. The handle B is attached to the base 25 by means of a bracket 22 at the front and another bracket 24 at the rear and these brackets are secured to the handle by means of a bolt 26. In the top of the shell or casing 16 there is formed an opening 28 immediately forward of the heel 18 30 within which are positioned a pair of terminal posts 34.

At the rear of the iron underneath the shell or casing the substantially Z shaped metal stamping above described is positioned and is designated 50 by the character 30. The upper leg of the Z shaped stamping formed in the shape of a plate 32 lies adjacent the casing partially closing the opening 28 and the other leg forming a cover plate 34 extends rearward adjacent the sole plate 55 and the heel 18. The plate 32 is provided at the forward end with a lug 36 adapted to engage a depression 38 in the shell adjacent the opening 28 by means of which it is partially anchored to the casing. Formed also on the plate are a pair 60

of projections 40 designed to position the plate within the opening 28. As viewed in Fig. 4 the plate 32 has a central slightly dished portion 42 in which are a pair of apertures 44.

5 The central bar 46 of the Z shaped section 30 is a plate like element somewhat trapezoidal in shape connecting the upper and lower plates 32 and 34. At the upper end 48 the element is rounded slightly where it presses against the 10 bottom of the casing 16 adjacent the hole 28. The lower plate 34 extends rearward substantially horizontal to the sole plate and is provided with a flange 50 extending downward to add rigidity to the plate and is provided also with an 15 upward extending rim 52 which fits snugly within edge of the heel 18.

The upper plate 32 extends almost completely across the opening 28 forming a rigid bottom for 20 the opening supported at both front and back upon which the pair of terminal posts 54 previously referred to are mounted. These are insulated from the plate by a series of mica washers 56 and are held in place by a nut 58. Ample clearance is provided between the terminal posts 25 54 and the adjacent edges of the holes 44 in the plate for insulating purposes. The terminal posts are connected by wires 60 to the heating element of the iron and a guard 62 protects the posts from accidental blows which would tend to 30 knock them out of alignment.

When the device is assembled the terminal posts are mounted and tightened into the holes 44 of the combined terminal support and heel cover which is then positioned upon the sole plate 35 on a shelf at the rear indicated as numeral 62 and in this position the lower leg 34 extends rearward as previously described. The lug 26 on the plate 32 is then positioned in the depression 38 provided for it adjacent the hole 28 in the casing 40 and the shell or casing is then lowered into place over the sole plate and there attached. Attachment consists of pressing the Z shaped member 45 30 between the casing and the sole plate and supporting it at one end by the lug 36. During the operation the rim 52 of the Z shaped plate is engaged frictionally within the inside portion 45 of the hollow heel plate. The Z shaped part by the means described is securely clamped between stationary parts forming a base for the iron.

50 Once the parts are in place the insulated terminal posts 54, become firmly attached to the casing by means of the rigid positioning thereon of the part 30 and its upper plate 32. Due to the support provided by the lug 36 resting upon the shell and the somewhat columnar support of the cross bar 46 the dished portion 42 supporting the terminal posts is made extremely rigid when once secured in place. The central bar 46 by resting at one end on the sole plate and at the other end against the shell, forms a spreader and reinforcement for the shell at a point of contact which is adjacent the terminal post opening 28 serving thus an added purpose.

Some changes may be made in the construction 65 and arrangement of the parts of my device without departing from the real spirit and purpose of my invention and it is my intention to cover by my claims any modified forms of structure or use of mechanical equivalents which may be reasonably included within their scope.

70 I claim as my invention:

1. In an electric sadiron structure including a sole plate, a pair of terminal posts and a shell having a terminal post opening and a hollow rearward extending heel, the combination of a

combined terminal post support and heel cover comprising a metal plate having upper and lower portions and a connecting plate therebetween, one of said portions being adapted to provide a support for the terminal posts having anchoring means for engaging a portion of the casing and locating means for positioning the leg in the opening, another of said portions having a rim positionable frictionally within the heel forming a cover for the under side of said heel. 10

2. In an electric sadiron structure including a sole plate, a pair of terminal posts and a shell having a terminal post opening and a hollow rearward extending heel, the combination of a combined terminal post support and heel cover comprising a metal plate having upper and lower portions and a connecting plate therebetween, one of said portions being provided with a plate for supporting the terminal posts, anchoring means for engaging a portion of the casing adjacent the opening and locating means for positioning the leg in the opening, the other of said portions having a rim positionable frictionally within a corresponding rim of the heel, said connecting plate having one end adapted to bear against the underside of the shell and the other end adapted to engage the sole plate to provide a reinforcement for the casing at the point of contact. 15 20

3. In an electric sadiron structure including a sole plate, a pair of terminal posts and a shell having a terminal post opening and a hollow rearward extending heel the combination of a combined terminal post support and heel cover including a stamping substantially Z shaped in cross section, said stamping having upper and lower plates forming legs and a connecting plate forming the cross bar, one of said legs being provided with a support for the terminal posts and a lug at the edge overlying a portion of the casing adjacent the opening and locating projections on the leg for positioning said leg in the opening, another of said legs being provided with a flange positionable frictionally within a rim formed on the heel forming a cover for the underside of said heel, said cross bar having one end adapted to bear against the underside of the shell and the other end adapted to engage the sole plate to provide a reinforcement for the casing at the point of contact.

4. In an electric sadiron structure including a sole plate, a pair of terminal posts and a shell having a terminal post opening therein, the combination of a combined terminal post support and shell reinforcement comprising a metal plate having portions bent at a sharp angle one with the other, one portion being adapted to fill the terminal post opening to support said posts and to engage the shell adjacent thereto, another portion being positioned with one end resting on the sole plate and the other engaged beneath the shell to provide a columnar support for said shell.

5. In an electric sadiron structure a base comprising a sole plate and shell held together as a unit, a pair of terminal posts, means forming an opening in the shell for the terminal posts, and a support for said posts comprising a bent metal plate having a portion positioned in said opening forming a mounting for said terminal posts, said plate being supported in the base by a pressure engagement therewith at three or more isolated points.

NORMAN D. VEA.
